Primary Examiner — Susan Bennett Hattan*Assistant Examiner* — Charles Hanson(74) *Attorney, Agent, or Firm* — Howard & Howard Attorneys PLLC**CLAIM**

The ornamental design for a prosthetic device, as shown and described.

DESCRIPTION

FIG. 1 is a perspective view of an embodiment of a prosthetic device.

FIG. 2 is a front elevational view of the prosthetic device of FIG. 1.

FIG. 3 is rear elevational view of the prosthetic device of FIG. 1.

FIG. 4 is a right side elevational view of the prosthetic device of FIG. 1.

FIG. 5 is a left side elevational view of the prosthetic device of FIG. 1.

FIG. 6 is top plan view of the prosthetic device of FIG. 1.

FIG. 7 is a bottom plan view of the prosthetic device of FIG. 1.

FIG. 8 is a perspective view of another embodiment of a prosthetic device.

FIG. 9 is a front elevational view of the prosthetic device of FIG. 8.

FIG. 10 is rear elevational view of the prosthetic device of FIG. 8.

FIG. 11 is a right side elevational view of the prosthetic device of FIG. 8.

FIG. 12 is a left side elevational view of the prosthetic device of FIG. 8.

FIG. 13 is top plan view of the prosthetic device of FIG. 8; and,

FIG. 14 is a bottom plan view of the prosthetic device of FIG. 8.
